UNITED STATES PATENT OFFICE

LEWIS SCHIELE, OF NEW YORK, N. Y., ASSIGNOR TO LEWIS SCHIELE & CO.,
OF SAME PLACE.

CORSET.

SPECIFICATION forming part of Letters Patent No. 389,015, dated September 4, 1888.

Application filed May 7, 1888. Serial No. 273,056. (No model.)

To all whom it may concern:

Be it known that I, LEWIS SCHIELE, of New York, in the county of New York and State of New York, have invented a new Improvement in Corsets; and I do hereby declare the following, when taken in connection with accompanying drawings and the letters of reference marked thereon, to be a full, clear, and exact description of the same, and which said drawings constitute part of this specification, and represent, in—

Figure 1, a front view showing the breast portion of the corset with the flap closed, broken lines indicating the flap turned to the right or left to open the breast; Fig. 2, a vertical central section through the breast portion of the corset; Fig. 3, the pintle part of the hinge detached; Fig. 4, the eye part of the hinge detached.

This invention relates to an improvement in that class of corsets which have an opening through the breast portion and a flap for closing the same, commonly called "nursing-corsets;" and the invention consists in combining with the flap and body of the corset a hinge presenting a segment-shaped pintle, so that the flap may swing downward and outward or be turned to the right or left on the segment-shaped pintle, as more fully hereinafter described.

The body of the corset may be of any of the usual constructions. Through the breast portion is an opening, A, across which opening at the top runs a band, B, preferably stayed.

C represents the flap, which is in area larger than the opening A. The flap is hinged to the body of the corset, so as to permit the opening or closing of the aperture in the corset.

The hinge is composed of the two parts D and E. The part D is best made in the form of a circular disk, near one edge of which an opening, a, is made, leaving a segment-shaped bar, d, which forms the pintle for the hinge. This part D is adapted to be attached to the body, and to this end the solid portion of the disk

below the opening a is pierced, as at e, through which eyelets may be introduced to secure it firmly to the body of the corset below the lower end of the flap C. The other part, E, may be made from any suitable material, as metal or fabric. In case of metal, it may be the shape as seen in Fig. 4, of a length so that when doubled it may embrace the lower end of the flap, as seen in Fig. 2. Before applying the part E of the hinge to the flap C it is passed through the opening a in the part D and doubled around the segmental-shaped pintle d, and then is secured to the flap, as represented in Fig. 2. This may be done by an eyelet, as shown, or otherwise. This forms a strong hinge between the flap and body of the corset, and one which permits the flap to be turned directly outward, as represented in broken lines, Fig. 2, or to swing to the right or left, as represented in broken lines, Fig. 1. The flap C is secured at the upper end by tucking it beneath the band B or otherwise.

The outline of the pintle portion of the hinge, as represented, is of a circular shape; but it will be understood that this may be of any desirable shape and more or less ornamental, it only being essential that there shall be a segment-shaped pintle upon which the eye portion of the hinge attached to the flap may be turned either to the right or left or outward and downward in opening.

I claim—

A nursing corset having an opening through the breast portion and provided with a flap, C, of an area larger than the opening in the said breast portion, combined with a hinge between the flap and body, the said hinge consisting of a metal segment-shaped pintle made fast to the one part and an eye looped about the segment made fast to the other part, substantially as described.

LEWIS SCHIELE.
